US00D608769S

(12) **United States Design Patent**
Bufe

(10) **Patent No.:** **US D608,769 S**
(45) **Date of Patent:** **** Jan. 26, 2010**

(54) **UHF ANTENNA**

(75) Inventor: **Henrik Bufe**, Dresden (DE)

(73) Assignee: **Muehlbauer AG**, Roding (DE)

(**) Term: **14 Years**

(21) Appl. No.: **29/310,407**

(22) Filed: **Aug. 14, 2008**

(30) **Foreign Application Priority Data**

Jul. 11, 2008 (EM) 000969183

(51) **LOC (9) Cl.** **14-03**

(52) **U.S. Cl.** **D14/230**

(58) **Field of Classification Search** ..... D14/138, D14/230-238, 299, 358; D12/42, 43; 343/700 MS, 343/700 R-705, 711-713, 741, 748, 767, 343/795, 819, 840, 846, 866, 871-908; 455/90.2, 455/90.3, 91, 128, 269, 344, 347, 562.1; 333/193, 195

See application file for complete search history.

(57) **CLAIM**

The ornamental design for a UHF antenna, as shown and described.

DESCRIPTION

The sole FIGURE is a top view of the UHF antenna applied on an area of a broken line contactless card.

The broken line showing of a contactless card illustrates environment only and forms no part of the claimed design.

1 Claim, 1 Drawing Sheet
